UNITED STATES PATENT OFFICE.

JOSEPH A. GAFNEY, OF BROOKLYN, NEW YORK.

BOTTLE.

No. 889,214.

Specification of Letters Patent. . Patented Sept. 22, 1908.

Application filed June 7, 1907. Serial No. 377,826.

To all whom it may concern:

Be it known that I, JOSEPH A. GAFNEY, a citizen of the United States, residing at 44 Stanhope street, Brooklyn, New York, have invented a new and useful Improvement in Bottles, of which the following is a specification.

My invention is an improvement in non-refillable bottles and in that class or type of such bottles which are provided with a loose, grooved stopper held in the bottle-neck and so arranged as to permit outflow of liquid when the bottle is inverted, but which normally seats downward and in such position prevents ingress of liquid.

The details of construction, arrangement, and operation of the invention are herein-after described, and shown in accompanying drawing, in which

20. Figure 1 is a longitudinal section of a bottle with my invention applied thereto. Fig. 2 is a top view. Fig. 3 is a cross section on the line 3—3 of Fig. 1. Fig. 4 is a side view of the bottle-stopper and rod attached thereto.
25. The bottle-neck B has at the base a shoulder b on which the conical glass stopper A rests. The lower portion of the stopper is smooth, and the upper one provided with vertical grooves C, the intervening ribs being angular in cross section. The top of the stopper is also grooved and ribbed radially. The grooves extend to the edge of the angles of the side ribs, and the intervening ribs are shorter, since they extend to the inner angles 35 or grooves between the side ribs. The latter are the highest parts of the top of the stopper. Above the chamber N in which the stopper A is free to move vertically, there is formed a series of vertical grooves D, and intervening angular ribs, the latter projecting inward so that the upper end of the stopper may seat upward against them. The number of grooves D is different from the number formed in the stopper A. Above the grooves 45 D is the passage J in the bottle-neck, which is enlarged from the lower end upward.

A rod H is attached to the stopper A, and it is made thin and hence more easily breakable at F. The rod extends up through the neck L and its purpose or function is to raise the stopper A from its seat b, so that liquid may be poured into the bottle. After the bottle has been filled, the rod is broken off at

F and the stopper drops to place thereby closing the passage. It will be understood 55 that the stopper is inserted into the bottle-neck in the process of manufacturing the bottle.

In order to empty the bottle, it is inverted or inclined at a suitable angle whereby the stopper A will move, by gravity, into the upper part of the chamber N, and the contents of the bottle will then pass through said chamber and around the enlarged head of the valve, and thus out through the neck of the 65 bottle. In other words, the grooves C, E, and D provide passages through which the liquid contents pass without serious hindrance. When the bottle is again placed upright, the stopper A will fall to place at b, 7 thereby closing the passage and preventing any liquid from entering the bottle proper. It will be seen that by the provision of grooves in the top of the stopper, not only are channels provided for outflow of liquid 71 and the stopper prevented from being raised by suction, but the several radial grooves guide a wire or other pointed instrument inserted from above. In other words, the wire thus inserted will strike in, and travel 80 out, any one of the radial grooves and thus reach a point at the side of the stopper which is intermediate of the side grooves or corrugations.

What I claim is—

1. The combination, with the bottle-neck having an enlarged chamber N, with valve seat b, and a series of vertical grooves D in the space above said chamber, of a conical valve A having a smooth lower portion and 90 its upper portion provided with longitudinal side grooves and ribs and its top portion with radial grooves and ribs, substantially as described.

2. The combination with the bottle-neck 95 having an enlarged chamber N with contracted valve seat below and a series of vertical grooves above, of a stopper formed of some easily frangible material, the upper portion of the stopper being grooved on the 100 side and top, as shown and described.

3. The combination of a bottle-neck having an enlarged chamber with narrowed seat below, and a series of vertical grooves in the space above, of a conical stopper adapted 105 to seat in the lower portion of said chamber

and provided in its upper portion with side grooves and ribs, and in the top with grooves and intervening ribs, the latter being higher than the tops of the side ribs, as shown and described.

In testimony whereof, I, have signed my name to this specification in the presence of

two subscribing witnesses, this fourth day of June 1907.

JOSEPH A. GAFNEY.
